UNITED STATES PATENT OFFICE.

FREDERICK W. BARRETT, OF SPRINGFIELD, OHIO

CUFF-HOLDER.

No. 835,593.

Specification of Letters Patent.

Patented Nov. 13, 1906.

Application filed May 28, 1904. Serial No. 210,204.

To all whom it may concern:

Be it known that I, FREDERICK W. BARRETT, a citizen of the United States, residing at Springfield, in the county of Clark and State of Ohio, have invented certain new and useful Improvements in Cuff-Holders, of which the following is a specification, reference being had therein to the accompanying drawings.

10 This invention relates to adjustable cuff-holders, and has for its object to provide means whereby the cuff may be readily adjusted and held so as to be exposed to a greater or less extent beyond the coat-sleeve while remaining in the same position with respect to the wristband of the shirt-sleeve to which it is attached.

15 To these ends my invention consists in certain novel features, which I will now proceed 20 to describe and will then particularly point out in the claims.

In the accompanying drawings, Figure 1 is a view showing my improved holder as applied 25 in use, a portion of the fabric of the shirt being removed to show the construction. Fig. 2 is a perspective view of a structure embodying my invention in one form. Fig. 3 is a longitudinal sectional view of the same. Fig. 4 is a perspective view of one of the elements 30 detached. Fig. 5 is a transverse sectional view of the casing or housing detached and on an enlarged scale. Fig. 6 is a longitudinal sectional view of one end of the same, also on an enlarged scale. Fig. 7 is a sectional view, 35 illustrating one mode of connecting the structure to the cuff; and Fig. 8 is a view similar to Fig. 3, illustrating a modification.

40 Referring to said drawings, 1 indicates the shirt-sleeve, having the usual wristband 2, with buttonholes 3, said shirt-sleeve being provided at a point above the wristband with a buttonhole 4, preferably formed in one edge of the wristband-placket, said buttonhole being preferably so arranged as to extend longitudinally of the shirt-sleeve.

45 5 indicates the cuff provided with the usual buttonholes 6 for connecting it to the wristband.

The holder is composed of two relatively 50 sliding members provided at or near their ends with engaging devices, preferably studs or buttons, for engaging the shirt-sleeve at one end and the wristband and cuff at the other, respectively, said engaging devices be-

ing preferably located on the same side of 55 both members—i. e., the outer sides—and the two members being longitudinally or telescopically movable relatively to each other upon the application of the proper degree of force while being normally held against 60 movement in any position to which they may be adjusted.

In my preferred form of construction, which is that shown in Figs. 2 to 6, inclusive, the two relatively slidable members are represented, respectively, by the reference-numerals 7 and 8 and are inclosed and frictionally held within a casing or housing 9. The member 7, which is engaged with the shirt-sleeve 1, is preferably provided with a 70 button or stud located on the outer face of said member near one end thereof, and comprising a shank 10 and a head 11, said head being preferably elongated in a direction transverse to the greatest length of the member 7 and relatively narrow. This form of button or stud is designed to coöperate with the buttonhole 4, formed in the placket of the shirt-sleeve and extending longitudinally of said sleeve, so that the elongated head 80 lies at right angles to the direction of elongation of the buttonhole when engaged therewith, as shown in Fig. 1, and thus prevents accidental disengagement, which is more apt to occur at this point, owing to the fact that 85 this portion of the shirt-sleeve is not usually as stiff as the wristband or cuff. The member 8 is provided at or near its outer end with an engaging device to engage the wristband and cuff, the same being preferably in the 90 form of a button or stud of any approved construction—such, for instance, as that shown, consisting of the shank 12 and head 13.

The casing or housing 9 is so constructed as to grip and hold the relatively movable 95 members in any position to which they may be adjusted, permitting them, however, to move when a sufficient force in excess of that to which they are subjected in ordinary use is applied to them for that purpose. To 100 effect this, I prefer to construct said housing of sheet metal having some resilience or elasticity, preferably sheet-brass, bent upon itself, as shown more particularly in Fig. 5, so as to form an inner slideway 14, in which 105 the member 7 fits and moves, and an outer slideway 15, in which the member 8 fits and moves. Said housing grips the members 7

2

and 8 tightly enough to hold them against ordinary strain in any position to which they may be adjusted, and to effect this I prefer to roughen the inner face of the outer wall of 5 each slideway by forming transverse rib-like projections 16 therein, which may be readily formed by pressing the metal of said walls inward at suitable intervals, the grooves arising from this pressing operation being 10 indicated by the reference-numeral 17. This roughening when employed may, however, be formed in any suitable way. Each of the members 7 and 8 is provided with a projection 18 to coöperate with the projections or roughened surface of the corresponding slideway when such roughened surface is employed, and this projection may be readily formed by striking up the metal of which the sliding member is composed, as indicated in 15 the drawings. I also provide stops to prevent the sliding members from being entirely withdrawn from the housing, and these are preferably formed in the manner shown in the drawings. Each of the members 7 and 8 20 has its inner extremity bent upon itself, as indicated at 19, thus forming a shoulder 20, and each of the slideways 14 and 15 has its outer wall provided with an extension in the direction in which the sliding member is 25 closed in said slideway projects, which extension is bent back upon the wall within the slideway, as indicated at 21, forming a shoulder 22, with which the shoulder 20 will engage to prevent the sliding member from being entirely withdrawn from the housing. 30 The device thus constructed is applied in use by connecting the end of one member thereof (in the present instance the member 7) to the shirt-sleeve at a point some distance from 35 the wristband, this being effected in the construction shown by engaging the button on the end of the member 7 with the buttonhole 4 of the shirt-sleeve placket. The button on the end of the member 8 is then engaged with 40 the wristband and cuff by means of the button or engaging device on the end of said member 8. This may be effected by passing said button through the buttonholes 3 of the wristband and also through the buttonholes 45 6 of the cuff. Another and very desirable way of effecting this engagement is illustrated in Fig. 7, in which 23 indicates a stud-button provided with a recess in its base and with head-engaging mechanism coöperating 50 with said recess to engage the head 13 of the button on the member 8. An illustration of a stud-button of this type may be found in United States Letters Patent No. 673,698, granted May 7, 1901, to George W. Buchanan. 55 This stud-button is engaged with the buttonholes of the cuff and with the head 13 in the manner illustrated in Fig. 7, serving thereby to connect the cuff to the adjuster. 60 Cuff holders as heretofore constructed 65 have not been devised as to maintain the cuff

in permanent relation with regard to the wristband of the shirt-sleeve, the adjustment being effected between the cuff and shirt-sleeve directly or between the cuff and coat-sleeve, so that when the cuff is adjusted 70 for a short exposure thereof beyond the coat-sleeve the wristband is apt to project and show prominently, while adjustment of the cuff for a longer exposure beyond the coat-sleeve is apt to cause the wristband to slip 75 out at the rear end of the cuff, thus spoiling the set of the cuff and discommodeing the wearer. These objections are obviated by the construction which I have devised, in which the adjuster not only so holds the cuff 80 relatively to the shirt-sleeve as to give the desired exposure thereof beyond the coat-sleeve, but also holds the cuff and wristband in proper permanent relation throughout the range of adjustment, preventing exposure or 85 slipping out of the wristband.

Another material advantage of my construction is that the adjustment of the parts may be effected very readily and without the necessity of even pulling up the coat-sleeve 90 to get at the adjuster. If it is desired to shorten the adjuster to decrease the exposure, this may be effected through the coat-sleeve by pressing the thumb against one end of the adjuster and one or more of the fingers of the 95 same hand against the other end, whereupon the members 7 and 8 may be slid toward each other in the housing by the pressure thus applied thereto until the adjuster is shortened up so as to give the desired exposure of the 100 cuff. The amount of cuff exposed may be increased with equal simplicity by simply grasping the end of the cuff and pulling it out until it is exposed to the desired extent, the members 7 and 8 yielding and sliding in the 105 housing to extend the adjuster to the necessary length. Thus the adjuster can be shortened by a mere pressure of the thumb and forefinger on the ends thereof, and lengthened by merely pulling the cuff; but the frictional engagement of the sliding members is sufficient to hold the parts in any position to which they may be thus adjusted against any disturbing force to which they may be subjected in ordinary use. It will be understood, of course, that the buttonholes 3 and 4 110 in the wristband and placket, respectively, are arranged, preferably, at such a distance apart when separated to the farthest degree of separation of which they are capable as to 115 be then at a distance from each other substantially equal to the maximum distance between the engaging devices by means of which the cuff-holder is engaged with said buttonholes. When the cuff-holder is applied and the parts are thus separated to the maximum distance, the adjustment takes place in the manner already described and causes a drawing together of the sleeve-band and the buttonhole 4. If the parts are thus 120 125 130

drawn together, the sleeve-band and button-hole 4 may be separated by the adjusting movement hereinbefore described, so as to adjust the position of the cuff. The button-hole 4 in the placket is provided for the special purpose of attaching the adjustable cuff-holder hereinbefore described, and the maximum distance between the buttonholes 3 and 4 must be greater than the minimum distance between the engaging devices at the ends of the cuff-holder. In Fig. 1 of the drawings the cuff-holder is shown extended to practically the maximum distance permitted by the maximum amount of separation of which the buttonholes of the wrist-band and placket are capable in the particular construction there chosen for purposes of illustration.

The form of holder shown in Figs. 2 to 6, inclusive, has the advantage of giving a wide range of adjustment, equal practically to the length of the housing and of the two sliding members 7 and 8. A simpler form of less but efficient range of adjustment is illustrated in Fig. 8, in which the housing (here indicated by the reference-numeral 24) constitutes one of the sliding members, being provided with a stud or button 25 upon its outer face and having a single slideway 26 to receive a sliding member 27, having a stud or button 28 on its outer face.

It will of course be understood that any approved form of engaging device may be substituted for the studs or buttons, and various other modifications will readily suggest themselves, so that I do not wish to be understood as limiting myself strictly to the precise details of construction hereinbefore described, and shown in the accompanying drawings.

Having thus fully described my invention, what I claim as new, and desire to secure by Letters Patent, is—

1. An adjustable cuff-holder comprising a casing or housing of resilient metal having one side roughened, a bar adapted to slide in said housing, a non-resilient projection on said bar adapted to engage the rough side of said resilient housing, and means carried by said housing and said bar for engaging the parts to be connected, substantially as described.

2. An adjustable cuff-holder comprising a casing or housing of resilient metal, transverse projections formed on one side thereof, a bar adapted to move in said resilient housing, a non-resilient projection on said bar adapted to engage the projections on said resilient housing, and means carried by said housing and said bar for engaging the parts to be connected, substantially as described.

3. An adjustable cuff-holder comprising a casing or housing formed of resilient sheet metal bent upon itself to form two parallel slideways, the walls whereof are internally roughened or serrated, the ends of said casing being bent to form stops, and a slideable bar fitting each slideway, each bar being formed of a flat metal strip having a projection to coöperate with the roughened surface of its way, having one end bent to form a stop, and provided on the other and projecting end with means for engaging one of the parts to be held, substantially as described.

In testimony whereof I affix my signature in presence of two witnesses.

FREDERICK W. BARRETT.
